UNITED STATES PATENT OFFICE

133,465

DESIGN FOR A COMBINED VALVE AND THERMOSTAT

William G. Cartter, Monrovia, Calif.

Application April 22, 1941, Serial No. 100,560

Term of patent 14 years

To all whom it may concern:

Be it known that I, William G. Cartter, a citizen of the United States, residing at Monrovia, in the county of Los Angeles, State of California, have invented a new, original, and ornamental Design for a Combined Valve and Thermostat, of which the following is a specification, reference being had to the accompanying drawing, forming a part thereof.

Figure 1 is a front elevational view of a combined valve and thermostat embodying my new design.

Figure 2 is a side elevational view thereof, taken from the right of Figure 1.

Figure 3 is a rear elevational view thereof.

The vertical lines on the portions inside the aperture located beneath the large screw head in Figure 1, indicate the color red.

I claim:

The ornamental design for a combined valve and thermostat, substantially as shown and described.

WILLIAM G. CARTTER.
